CLAIM

The ornamental design for a rail mounting apparatus, as shown and described.

DESCRIPTION

The invention described and claimed herein may be manufactured, used and licensed by or for the U.S. Government for U.S. Government purposes.

FIG. 1 is a perspective view of a rail mounting apparatus showing our new design;

FIG. 2 is a front elevation view thereof;

FIG. 3. Is a back elevation view thereof;

FIG. 4 is a left side elevation view thereof;

FIG. 5 is a top plan view thereof; and,

FIG. 6 is a bottom plan view thereof.

The broken line showing of portions of the rail mounting apparatus and a rail mount for a rifle or machine gun in FIG. 1 is included for the purpose of illustrating environment and forms no part of the claimed design.
